UNITED STATES PATENT OFFICE.

JACOB A. RAPPAPORT, OF BROOKLYN, NEW YORK, ASSIGNOR TO RELIANCE FIRE-PROOF DOOR COMPANY, OF BROOKLYN, NEW YORK, A CORPORATION OF NEW YORK.

WINDOW CONSTRUCTION AND THE LIKE.

Application filed October 26, 1922. Serial No. 596,986.

To all whom it may concern:

Be it known that I, JACOB A. RAPPAPORT, a citizen of the United States, and a resident of the borough of Brooklyn, county of 5 Kings, city and State of New York, have invented an Improvement in Window Constructions and the like, of which the following is a specification.

My present invention relates to metal 10 window frames, particularly the metal jambs, parting strips and glass moldings for such frames, and also the window sash frames, particularly the side rails thereof.

It is an object of the present invention to 15 provide devices of the general character referred to above, which shall be very simple in construction, which shall be easy to manufacture and to assemble, which shall be of strong, rigid construction, which shall 20 operate smoothly and efficiently, which shall be neat and attractive in appearance, and which shall provide the desired protection against wind and rain for the various parts 25 of the window frame and for the interiors of the structures to which the window frames of the present invention may be applied, all of these enumerated qualities being such as to highly recommend these devices to builders, contractors, architects 30 and the like.

In the accompanying specification I shall describe, and in the annexed drawing show, a preferred embodiment of the present invention. It is, however, to be clearly understood that my invention is not limited 35 to the particular embodiment thereof herein shown and described for purposes of illustration only.

Referring to the drawing, wherein I have 40 illustrated the aforesaid illustrative embodiment of the present invention:

Figure 1 is a vertical sectional view, partly broken away, of the window frame and surrounding structure, as a whole, showing 45 all the pulley boxes, and the upper and lower sashes within the window frame; and

Figure 2 is a horizontal sectional view, also partly broken away, of the device shown in Figure 1 of the drawing.

50 Referring to said illustrative embodiment of the present invention, the same comprises the usual surrounding masonry within which the window is set, the masonry being indicated by reference character 10. The

masonry includes the usual upper portion 55 11, the lower portion 12, the sill brick 13, and the side members 14 and 15, defining between them the opening 16 and the space 17 within which the window frame is positioned.

The metal frame, generally indicated by reference character 18, and the various metal portions of which the same may be made, may be fabricated from extruded bronze or 60 equivalent metal, or of bronze or other metal which has been given the desired shape and form by any other convenient method of manufacture. The frame 18 comprises the metal sill 20 having the outwardly and downwardly inclined portion 21 and the 65 flange portion 22 cooperating with the sill brick 13. The inner portion 23 of the metal sill 20 may have any desired form. However I prefer to give it the form shown in 70 the drawing.

Between the outer portion 21 and the inner portion 23 of the metal sill 20 is an intermediate, raised portion 24 which comprises an outer slightly inclined wall 25, an inner substantially vertical portion 26, 80 which is preferably shorter than the outer wall 25, and an intermediate wall 27 joining the outer wall 25 and the inner wall 26. The intermediate wall 27 is slightly outwardly 85 and downwardly inclined, and is provided adjacent its central portion with a longitudinal bead 28 for a purpose subsequently to be described in greater detail.

Cooperating with the metal sill 20 are a plurality of window jambs, generally indicated by reference character 30. Since the two jambs are substantially identical, it will be sufficient, for the purposes of the present description, merely to describe one 90 of these jambs. Each jamb 30 comprises a main central web portion 31 and laterally 95 extending L-shaped flanges 32 and 33, respectively.

At an intermediate portion of the same, the web portion 31 is provided with a depressed portion 33, one face of which, as the face 34, is generally inclined for a purpose subsequently to be described in greater detail. Cooperating with each jamb 30 is a stop 35 and an extension 36, the stop and extension serving to properly position the window sashes when in place. For a purpose subsequently to be described, stop 35

is provided, with a channel 35' and the extension 36 with a channel 36'. The channels 35' and 36' are preferably of wedge-shaped cross sections with the bases of the wedges adjacent the faces of the members 35 and 36 in which the respective channels 35' and 36' are provided.

Cooperating with the L-shaped flanges 32 and 33 is a sheet metal weight box cover 37 the ends of which, as indicated at 38, are turned or flanged over the transverse portions of the respective flanges 32 and 33 to fasten and position the weight box covers 37 in place on the respective jambs 30.

The remaining portion of the metal window frame 18 is a head, generally designated by reference character 40, and comprising a main web portion 41 having a central depressed portion 42 and laterally extending L-shaped flanges 43 and 44. Cooperating with the L-shaped flanges 43 and 44 of the head 40 is a sheet metal pulley box cover, indicated by reference character 45, portions of which, as indicated by 46 and 46', respectively, are bent or flanged over the transverse portions of the laterally extending flanges of 43 and 44 to properly position and retain the pulley box cover in place. The pulleys are generally indicated

by reference character 47, and may be of any suitable or desired type of construction.

Cooperating with the window jambs 30 are the parting strips, generally designated by reference character 50. Since the two parting strips are substantially identical, it will be sufficient for the purposes of the present invention to describe merely one of these strips. Each parting strip comprises a main central web portion 51 having a substantially centrally disposed channel or depression 52, and the flange portions 53 and 54. The flange portions 53 and 54 are provided with the longitudinally disposed channels or depressions 53' and 54' in the respective outer faces of the flanges 53 and 54. It will be noted further that the flange 53 is provided with an inclined laterally disposed and inwardly and downwardly turned portion 53'', for the purpose of permitting the insertion of the parting strips, as subsequently described in greater detail.

Within the depression 52, or at least partly contained within the same, are suitable fastening means, indicated by reference character 55, for suitably attaching the parting strips to the window frame, in this case to the window jambs 30. Covering the depression 52 is a rubbing strip 56 which covers the heads of the screws or other fastening devices 55 partly contained within the channel or depression 52.

The upper window sash, here generally indicated by reference character 60, comprises a top rail 61 provided with the inwardly expanding L-shaped flange 61', which, by co-

operation with the glass molding 62, assists in positioning the pane of glass 63.

The upper sash 60 also includes the side rails 64, each comprising a central web portion 65 and the outwardly extending flange portions 66 and 67. Each outwardly extending flange 66' and 67' is provided with a raised bead or portion 66' and 67', respectively, of which the raised portion 66' cooperates with the channel or depression 54' of the parting strip 50, while the raised portion 67' cooperates with the similarly shaped channel or depression 53' of the extension 36 of the window jamb 30. The beads or raised portions 66' and 67' are, it will be noted, of substantially wedge-shaped cross-section.

The meeting rail 70 of the upper sash 60 also comprises a tubular member, generally indicated by reference character 71. The member 71 has a top wall 72, a bottom wall 73, and the side walls 74 and 75. It is not deemed necessary here to describe in detail the exact construction of the side walls 74 and 75, since this construction is made the subject of another application for Letters Patent filed by me of even date herewith, entitled "Meeting rail for windows and the like," and bearing Serial No. 596,989.

It is sufficient, however, to state here that the side wall 75 is provided with a tongue-like projection 75' defining a groove 75'' for cooperation with the similarly shaped tongue-like projection and groove of the meeting rail of the lower sash, while the side wall 74 is provided with an L-shaped extension 74', which, by cooperation with the glass molding 62, helps to position and protect the pane of glass 63. It may here also be stated that the general inclination of the side wall 75 is upward and outward, thus giving ideal protection for the interior of the structure to which the window is applied, and for the various other parts of the window itself, against the ingress of wind and rain.

The lower sash, here generally indicated by reference character 80, comprises the bottom rail 81, of tubular construction, provided with the flanges 82 and 82', and with the indented portion 83' for receiving the bead 28 of the raised portion 27 and the metal sill 20. The bottom rail 81 is provided with an L-shaped extension 84, which, by cooperation with the glass molding 85, serves to retain and protect the pane of glass 86.

The side rails 87 of the lower sash 80 are constructed in the same manner as the side rail 64 of the upper sash 60, and need not be described in greater detail herein, except to note that the two flange members 88 and 89 of the side rails 87 of the lower sash 80 are provided with the respective beads 88' and 89' of which the bead or raised portion 88'

of the flange 88 slides in the groove 35" of the glass molding 35, while the bead or raised portion 89' of the flange 89 slides within the groove 53' of the parting strip 50.

5 The meeting rail 90 of the lower sash 80 comprises a tubular member 91 having the top wall 92, the bottom wall 93, and the side walls 94 and 95. Since this meeting rail has been made the subject of the other 10 copending application already referred to by me above, it will not be necessary to describe the same here in detail, except to state that the side wall 94 is provided with an L-shaped extension 94' for assisting in the retention and protection of the pane of glass 86, while the side wall 95 is provided with a tongue-like projection 95' defining the recess 95" for cooperation with the similarly shaped tongue-like projection and recess 75' and 75", respectively, of the meeting rail 70 of the upper sash 60.

25 The manner of assembling the window frame and window described above, and the advantages of the same in use, will be substantially clear from the foregoing description. After the sill, jambs and head of the window have been properly positioned and fastened within the masonry of the structure, the upper sash 60 is placed within the 30 frame, and the pulley weights are attached to the sash.

35 Thereafter the parting strips 50 are inserted in place, this insertion being facilitated by the inclination of the portion 53" of each parting strip. Thereafter the fastening means 55 are applied for removably positioning the parting strips in place in the window jambs 30. At this point the rubbing strips 56, which may be of bronze or other suitable metal, are applied to cover the heads of the screws or other fastening means 55.

40 The lower sash 80 is then placed within the window frame, and the stop beads 35 are then applied to retain the lower sash 80 in proper position.

45 The advantages of the foregoing construction are numerous and of great practical importance. The device is simple in construction and easy and economical to manufacture and to assemble. This is particularly true where, as is preferred, the various metal portions of the frame and of the sashes are made of extruded bronze or equivalent metal, or of suitable metal fabricated by some other convenient or desired process.

50 The device is at the same time strong and rigid in construction, operates very easily and conveniently, and is very neat and attractive in appearance, all of which qualities render the device much in demand by builders, contractors, architects and the like. At the same time the device affords more dependable protection for the various parts 55 of the frames and of the sashes, as well as

for the interiors of the structures to which the windows may be applied, against the ingress of wind and rain.

The provision, in the device shown and described by way of example herein, of the 70 cooperating wedge or other shaped channels or depressions, and of the beads or raised portions, operates admirably to provide a construction of window and sash frames which serves to accomplish the various desired results set forth in detail in the earlier part of this specification.

What I claim is:

1. In a metal window frame, a window 80 jamb comprising a main central web portion provided with a substantially centrally disposed channel one lateral wall of which is outwardly inclined, and an outer extension in the form of a transversely disposed flange provided with a channel in the inner face 85 thereof.

2. In a metal window frame, a window 90 jamb comprising a main central web portion formed with a substantially centrally disposed channel of wedge-shaped cross section one lateral face of which is outwardly inclined, and an outer extension in the form of a transversely disposed flange provided with a channel in the inner face thereof disposed substantially at right angles to said 95 first-mentioned channel.

3. In a metal window frame, a window 100 jamb comprising a main central web portion formed with a substantially centrally disposed channel of wedge-shaped cross section one lateral face of which is outwardly inclined, and an outer extension in the form of a transversely disposed flange provided with a channel in the inner face thereof disposed substantially at right angles to said 105 first-mentioned channel, the base of said wedge-shaped channel being at the outer surface of said flange.

4. In a metal window frame, a window 110 jamb comprising a main central web portion provided with a substantially centrally disposed channel one lateral face of which is outwardly inclined, in combination with a hollow stop member provided with a channel in the inner face thereof disposed substantially at right angles to said first-mentioned channel.

5. In a metal window frame, a window 115 jamb comprising a main central web portion provided with a substantially centrally disposed channel one lateral face of which is outwardly inclined, and an outer extension in the form of a transversely disposed flange provided with a channel in the inner face thereof, in combination with a detachable stop member provided with a channel in the inner face thereof, the channel in the stop member being disposed oppositely to that in the transversely disposed flange.

6. In a metal window frame, a window 130

jamb comprising a main central web portion provided with a substantially centrally disposed channel of wedge-shaped cross section one lateral face of which is outwardly inclined, and an outer extension in the form of a transversely disposed flange provided with a channel in the inner face thereof, in combination with a detachable stop member provided with a channel of wedge-shaped cross section in the inner face thereof, the last two mentioned channels being disposed opposite each other and in substantially the same plane.

7. In a metal window frame, a parting strip having a central web portion and a plurality of depending flange portions, each of said flange portions being provided with a groove in the outer face thereof.

8. In a metal window frame, a parting strip having a central web portion and a plurality of depending flange portions, each of said flange portions being provided with a groove in the outer face thereof, one of said flange portions having associated there-

with a member presenting an inclined contacting surface.

9. In a metal window frame, a jamb formed with an integral flange projecting substantially at right angles to the general plane of the jamb and formed on its inner face with a longitudinally extending groove, and formed intermediate its ends with a channel two walls of which are disposed at right angles to each other and the third at an angle to the other two, a parting member formed with flanges to snugly fit in said channel and detachably secured to said jamb, said parting member being formed with a groove at each side thereof disposed in the same plane as the groove in the flange, and a stop member secured adjacent the other end of the jamb and also formed with a groove in its inner face disposed in the same plane as the other grooves.

In testimony, whereof, I have signed my name to this specification this 30th day of September, 1922.

JACOB A. RAPPAPORT.
